UNITED STATES PATENT OFFICE.

HENRY G. LIEBZEIT, OF SHEBOYGAN FALLS, WISCONSIN.

OIL-SUPPLY SYSTEM FOR BURNERS.

1,212,078.

Specification of Letters Patent.

Patented Jan. 9, 1917.

Application filed July 24, 1915. Serial No. 41,721.

To all whom it may concern:

Be it known that I, HENRY G. LIEBZEIT, a citizen of the United States, residing at Sheboygan Falls, in the county of Sheboygan 5 and State of Wisconsin, have invented certain new and useful Improvements in Oil-Supply Systems for Burners, of which the following is a specification, reference being had to the accompanying drawings.

10 This invention relates to certain improvements in oil supply systems for burners; and an object of the invention is to provide a system of this general character having novel and improved means whereby a steady 15 pressure is maintained on the oil and thus resulting in a steady flame.

The invention consists in the details of construction and in the combination and arrangement of the several parts of my 20 improved oil supply system for burners whereby certain important advantages are attained and the device is rendered simpler, less expensive and otherwise more convenient and advantageous for use, all as will be herein- 25 after more fully set forth.

The novel features of the invention will be carefully defined in the appended claim.

In order that my invention may be the better understood, I will now proceed to describe the same with reference to the accompanying drawings, wherein the figure is a 30 diagrammatic view, partly in elevation and partly in section, illustrating a system arranged in accordance with an embodiment 35 of my invention.

As disclosed in the accompanying drawings, 1 denotes a tank for the storage of compressed air of a pressure to 200 pounds test, and 2 indicates an oil tank of the same test 40 as the tank 1 and said tanks 1 and 2 are in communication one with the other through the medium of the conduit 3, said conduit having interposed therein the reducing valve 4 whereby a pressure may be maintained 45 upon the oil within the tank 2 less than the pressure within the tank 1.

As herein embodied, air is adapted to be stored within the tank 1 under a pressure of substantially 200 pounds, said air being 50 delivered within the tank 1 under the influence of the compression pump 5 which may be of any desired type and the valve 4 is adapted to be regulated so as to maintain the pressure of the air delivered within the

tank 2 at a point between 70 and 80 pounds 55 whereby it will be perceived that a steady pressure on the oil within the tank 2 is assured which will result in a steady flame at the burner 6 in communication with the tank 2 through the conduit 7. The burner 6, 60 as herein embodied, is constructed in accordance with the burner described and claimed in my Patent, No. 1,129,212, dated Feb. 23, 1915.

The conduit 3 at a point intermediate the 65 tank 1 and the reduced valve 4 has in communication therewith the gage 8 whereby the pressure within the tank may be readily determined and in communication with the conduit 3 intermediate the tank 2 and the 70 valve 4 is a second gage 9 whereby the pressure upon the oil may be readily ascertained. The conduit 3 has also interposed therein at a point intermediate the tank 1 and the valve 4 a cut-off 10 whereby the pressure of 75 the air within the tank 2 may be shut off when said tank 2 is being filled and the conduit or pipe 7 has the valve 11 interposed therein, for a purpose which is believed to be self-evident. The conduit 3 has also interposed therein and at a point between the valve 4 and the gage 9 a check valve 12 operating to prevent return flow of the air to the tank 1.

From the foregoing description, it is 80 thought to be obvious that an oil supply system for burners constructed in accordance with my invention is of an extremely simple and comparatively inexpensive nature and is particularly well adapted for use 85 by reason of the convenience and facility with which it may be assembled, and it will also be obvious that my invention is susceptible of some change and modification without material departure from the principles 90 and spirit thereof and for this reason I do not wish to be understood as limiting myself to the precise arrangement and formation of the several parts herein shown in carrying out my invention in practice. 100

I claim:

In combination, an oil tank, an air tank in communication therewith and adapted to contain air under pressure, a reducing valve interposed in the connection between the 105 tanks, a burner, a connection between the burner and the oil tank, a gage interposed in the connection between the reducing valve

and the air tank, a second gage interposed in the connection between the oil tank and the valve, a cut-off valve interposed in the first named connection intermediate the air tank and the second named gage, and a cut-off interposed in the connection between the oil tank and the burner.

Copies of this patent may be obtained for five cents each, by addressing the "Commissioner of Patents, Washington, D. C."

In testimony whereof I hereunto affix my signature in the presence of two witnesses.

HENRY G. LIEBZEIT.
